UNITED STATES PATENT OFFICE.

ARTHUR E. ALLUM, OF NEW YORK, N. Y.

TUBULAR WAISTBAND.

1,077,250.

Specification of Letters Patent.

Patented Nov. 4, 1913.

Application filed December 9, 1910. Serial No. 596,472.

To all whom it may concern:

Be it known that I, ARTHUR E. ALLUM, a citizen of the United States, residing at New York, in the county of New York and 5 State of New York, have invented certain new and useful Improvements in Tubular Waistbands, of which the following is a specification.

This invention relates to an improvement 10 in waist bands for garments, the object being to form the waist band of a pair of trousers in such a manner as to accommodate a belt without exposing the same.

Other objects and advantages will be apparent from the following description and it will be understood that changes in the specific structure shown and described may be made within the scope of the claim without departing from the spirit of the invention.

In the drawings: Figure 1 is a view of the garment with the waist band attached, Fig. 2 a view of the waist band removed, Fig. 3 a sectional view, the belt being positioned 25 within the band, and Fig. 4 a similar view with the belt removed.

The band or tunnel consists of the portion 10, which is formed of the same material as the garment, said material being 30 folded on the line A, the folded portion 11 having secured thereto, a lining 12, said lining and said material being adapted to embrace a strip of canvas 14 which is doubled or folded centrally and longitudinally 35 so that the free ends or edges of the strip so folded lie at the bottom or lower edge of the band or tunnel. The folded end portion 11 of the material extends over the upper longitudinal edge of the canvas, while 40 the lining 12 is also folded at its upper edge, the lining, the canvas and the adjacent folded edge of the facing material being secured together by a single row of stitching 14', the three pieces of material forming the tubular opening 15 after the band has been 45 stitched along the line 16 to the garment, by a single row of stitching thus forming a housing for a belt 17, this belt may be of

the usual construction, or the same may be of cloth, and secured within the opening at 50 the rear thereof, the ordinary tightening means being employed.

By constructing and arranging the various portions of the belt holder or waistband as hereinabove described, I am enabled to 55 obtain certain important advantages. One is that buttons such as are commonly sewn upon the inner face of the waistbands of trousers designed especially for summer wear may be readily attached to the lining 60 either by stitching or by eyelets, without breaking the continuity of the canvas tube, and therefore the tube will always present a smooth interior surface along which the belt may readily slide. Another advantage 65 is that the waistband itself while possessing a proper degree of flexibility is so stiffened when the belt is placed therein that the trousers will be properly draped upon the person thereby obtaining a neat appearance. 70 Another advantage is that the interior canvas tube forms the wearing surface of the belt and protects the outside facing and the lining from wear caused by the rubbing of the belt as it works in the tube under the 75 movement of the person. This last is an important feature inasmuch as the waistband will greatly outlast an ordinary waistband formed of the thickness of material of the garment itself.

It will be seen from the foregoing that a band constructed in this manner will effectively conceal the supporting member, and at the same time form a neat device.

What is claimed is:

The combination with a pair of trousers, of a tubular waistband therefor comprising an inner stiffening and protecting section formed from a strip of material folded longitudinally medially, an outer facing strip 90 of material having its upper edge portion folded over to overlap the fold in the first mentioned strip and having its lower edge portion folded to engage the edges of the first mentioned strip, and a lining strip having 95 its upper edge portion united by a line of

80

85

stitching to the folded over upper edge of the facing strip and having its lower edge portion united by a line of stitching with the folded over lower edge portion of the 5 facing strip and the lower edges of the first mentioned folded strip, the band being united at its lower edge portion to the garment at the waist line of the latter and

lying bodily above the said waist line of the garment.

In testimony whereof I affix my signature, in the presence of two witnesses.

ARTHUR E. ALLUM.
